UNITED STATES PATENT OFFICE.

MAXWELL A. WEST, OF PORTLAND, OREGON.

BURGLAR ALARM.

Application filed March 28, 1927. Serial No. 178,861.

This invention relates generally to devices for protection against burglary, and particularly to a special form of burglar alarm.

The main object of this invention is to provide an exceedingly simple and efficient burglar alarm which will be easy to manufacture and not readily put out of commission.

The second object is to produce a burglar alarm entirely independent of electrically 10 operated mechanisms or spring motor devices.

The third object is to so construct the device that it can be set by a person in a room before or after a door is closed, but once the door is closed a subsequent opening thereof will 15 sound the alarm.

These, and other objects, will become more apparent from the specification following as illustrated in the accompanying drawing, in which:

20 Figure 1 is a plan of the device of which Figure 2 is a side elevation and Figure 3 a perspective view of a door showing one way in which the alarm can be set. Figure 4 is a horizontal section taken along the line 4—4 25 in Figure 3 showing the door about to be closed in full lines and just coming in contact with the device in dotted lines. Figure 5 is a view similar to Figure 4 but showing the alarm moved out of the way by the door.

30 Figure 6 shows the door closed and the alarm in the position of rest. Figure 7 is an enlarged perspective view of the preferred form 35 of latch member employed in this device.

Similar numbers of reference refer to similar parts throughout the several views.

Referring in detail to the drawing, the device itself consists of a resilient member 10 having one end 11 sharpened to form a point and having attached to its opposite end 12 a 40 bell 13.

The manner of attaching the bell to the end 12 is unimportant and will depend upon the type of bell employed and other factors. In this case it is shown as a riveted connection 45 in which the end 12 passes between the lugs 14 of the bell 13 and is secured by the rivet 15.

Near the middle of the flexible member 10 is secured a latch member 16 whose side 17 is toward the bell and whose face 18 is toward 50 the point 11. The face 18 is preferably slightly undercut, as indicated, and the latch 16 is attached to the member 10 by means of the rivets 19, or in any other convenient manner.

The latch 16 may be made of rubber for the 55 purpose of securing better frictional engagement with the door 20 or it may be made of

other material and provided with a friction face which will not mar the door.

In the form shown in Figures 1 and 2 the resilient member 21 itself is bent to form the 60 faces 22 and 23, the latter of which is provided with a rubber cover 24 which engages the door 20 when it is opened. A connecting tie 25 is placed across the bent portion of the member 21 and secured thereto by means of 65 rivets 26, or in any other convenient manner such as welding or otherwise joining the two elements.

In some cases it is preferable to slip a piece of rubber tubing over the portions 22 and 23 70 in order that no metallic contact shall be had with the door 20.

In operation the point 11 is thrust into the door jamb 27 or if a moulding stop is employed it is thrust in the crack between the 75 moulding stop and the jamb itself. When the door is closed it engages the member 17 and pushes the device out of the way, but, after the door has passed the latch and approached the closed position shown in Figure 80 85 6, the latch 17 takes up its position behind the door 20 so that a subsequent opening of the door causes it to engage the face 18 and, owing to the undercut nature of the face 18, to vibrate the bell 13, and at the same time withdraw the point 11 from its place in the 90 woodwork of the door casing causing it to fall to the floor with a noise which will be sufficient to waken the soundest sleeper, if not to frighten away the most intrepid 95 burglar.

It can be seen that the same condition will arise if the device is inserted on the top of the door instead of at its side. Also when used in connection with windows the movement 95 up or down would cause it to fall with an accompanying loud noise.

I am aware that many modifications of this device could be constructed without departing from the spirit of this invention, for example: Instead of the flat resilient member 10 a round wire could be employed and a conical latch could be used instead of the wedge-shaped form. Also many other types of bells could be used and shapes and varieties of 100 latches. I therefore do not intend to limit myself to this precise form of the device, but I intend to cover all such forms thereof as fall naturally and fairly within the appended 105 claims.

I claim:

1. A burglar alarm having, in combination,

a resilient pointed blade member adapted to be thrust into the woodwork of a door jamb between the door and its casing; a bell attached to said blade forming a handle member therefor; and a latch formed on one side of said blade having a sloping side facing said bell and a shouldered side facing the pointed end of said blade, said latch having a soft face adapted to prevent the marring of said door and to increase the frictional engagement between said door and shoulder while said door is being opened until said bell is completely released from its support.

2. In a burglar alarm, the combination of a resilient blade having a bell mounted at one end thereof forming a handle for said blade and having the opposite end of said blade pointed, together with a latch means mounted

on one side of said blade having one sloping side facing said bell and having one undercut shouldered side facing said pointed end, said undercut side having a resilient friction surface provided on its door-engaging side.

3. In a burglar alarm, the combination of a resilient blade member having one sharpened end and having a bell attached to its opposite end said blade having a latch positioned near the middle of its length said latch having a sloping side facing said bell, and a shouldered side facing its pointed end.

4. A burglar alarm consisting of a blade, a bell attached to said blade, and a stop formed on said blade adapted to engage a door in a manner that the opening movement of the door will release said blade from its support.

MAXWELL A. WEST.
